(57) **CLAIM**

The ornamental design for an electrical box, as shown and described.

DESCRIPTION

FIG. 1 is a rear, left and top perspective view of an electrical box, showing my new design;

FIG. 2 is a front, right and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is an enlarged view of a portion labeled as 9 on FIG. 2; and,

FIG. 10 is an enlarged view of a portion labeled as 10 on FIG. 8.

The long dash-short dash broken lines depict enlargement boundaries that form no part of the claim. The evenly broken lines illustrate portions of the article that form no part of the claimed design.

1 Claim, 10 Drawing Sheets

FIG. 1

FIG. 2

FIG. 3

FIG. 4

FIG. 5

FIG. 6

FIG. 7

FIG. 8

FIG. 10
